WILLIAM L. MORRIS, OF FORT WAYNE, INDIANA, ASSIGNOR TO S. F. BOWSER & CO., INC., OF FORT WAYNE, INDIANA, A CORPORATION OF INDIANA.

OIL-DRIP-RETURN SYSTEM.

1,141,649.

Specification of Letters Patent.

Patented June 1, 1915.

Application filed February 14, 1912. Serial No. 677,606.

To all whom it may concern:

Be it known that I, WILLIAM L. MORRIS, a citizen of the United States, residing at Fort Wayne, in the county of Allen and State of Indiana, have invented certain new and useful Improvements in Oil-Drip-Return Systems, of which the following is a specification.

My invention relates to improvements in oil return systems, and the primary object of my invention is to provide an improved system embodying means for conveying or returning the waste or used oil from the bearings and other lubricated parts of engines, machines and the like, to a common point, such as an oil filter, so that the oil may be reused.

A further object of my invention is to provide an improved system embodying an organization of drains and connections arranged for minimizing clogging or blocking, and embodying means for gaining access and cleaning the clogged parts without interfering with or interruption in the operation of the other portions thereof and thereby avoiding the shutting down of the entire system when some portion thereof becomes clogged.

A further object is to provide an improved oil return system embodying means whereby the location of the clogged portion or portions may be readily determined or ascertained without interruption or disturbance of the operation of the system.

With these and other hereinafter appearing objects in view, my invention consists in the features of novelty disclosed in the construction, combination and arrangements of parts hereinafter described and claimed, and shown in the accompanying drawings illustrating one embodiment of my invention, and in which—

Figure 1 is a diagrammatic view illustrating my invention as applied to a bank of three cross-compound engines; and Fig. 2 is an enlarged perspective illustrating the oil drains and other parts associated with one engine. Fig. 3 is an enlarged vertical sectional view of one of the manifolds or junction boxes showing how the drains enter it.

In the drawings I have illustrated my invention as embodied in an oil drip return system arranged to adapt it to the require-

ments of a group or bank of three cross-compound engines, but it is to be clearly understood that my invention is applicable to other machines and groupings or arrangements thereof from which oil is to be recovered. It is generally the practice to place shallow pans beneath the bearings and other lubricated parts of engines and other machines to catch the oil drippings therefrom and prevent the oil from running over the floor, and it is in connection with such an arrangement that I will describe my invention. These pans are illustrated as at A and in the particular arrangement shown, those associated with each engine are grouped, so to speak. Generally these pans have outlets comprising drip pots B, which pass through the floor and provide suitable means by which the drains may be connected.

At conveniently accessible points near several pans I place junction boxes or drip manifolds C, and to the manifolds I run branch or drain pipes D from the drip pots B of the several pans so that the manifolds constitute common points to which the oil from the particular pans connected to each manifold may flow. Preferably I provide each pan with a single drain pipe D connected to the manifold, and in a gravity system these drains are pitched or inclined sufficiently to cause the oil to flow along but not fill the drains.

I generally locate an oil main E as close as possible to the manifolds C, so that the main E will be common to a plurality of groups of drip pans, or in cases where the drip pans cannot be conveniently grouped, the main E may be common to a plurality of single drains D. This is clearly illustrated in Figs. 1 and 2. In this particular arrangement the main E runs through the several manifolds C of the groups X, for instance, inclosed by the dotted lines X¹ so that the several drains thereof feed oil directly to the main E through their respective manifolds.

In the case of the other groups Y, such as those inclosed by the dotted line Y¹, it is deemed advisable, because of their greater distance from the main E, to connect the manifolds thereof with main E by means of straight direct feeders G. These feeders enter the main through the manifolds of groups X and for this reason the manifolds

of groups X are sufficiently larger in capacity to accommodate the flow of oil from both groups. Like the drains D, the feeders G and main E are pitched sufficiently so that the oil flows generally in one direction through the system and it is obvious that the main E may deliver oil directly to the oil filters (not shown), or it may discharge the oil into a still larger main.

10 The manifolds C may be of any suitable kind, but I find the best results are obtained by making them of metal, rectangular in shape as clearly shown in the drawings, and providing removable screw caps 15 C¹, which seal the manifolds. Any suitable means may be employed for connecting the various pipes to the manifold.

In Fig. 3 I have shown the drain pipes D and the main E screwed or threaded into 20 the side walls C² of the manifold so that their ends are preferably flush with the inner faces of said walls. The various pipes are arranged in such manner that the oil enters the manifolds at a higher level than 25 it leaves them; for instance, in Fig. 3 it will be seen that the drain pipes D enter the manifold at the upper part thereof, and the main E through which the oil leaves is connected to the manifold at the lower portion 30 thereof. Furthermore, the pipes through which the oil leaves the manifolds are preferably large enough to carry away the oil as fast as it enters the manifolds. Hence in the normal operation of the system the manifolds do not fill with oil. 35 Should a pipe in the system become clogged so as to obstruct the passage of oil therethrough it will cause the manifold, from which it had been taking the oil, to fill.

40 This can be readily located by backing off or unscrewing the cap of a manifold which has a clogged line running into it, and if the oil oozes out it indicates that the manifold is filled and that the system is clogged 45 farther on down. This is done with the several manifolds in the line until a manifold is located which does not leak oil when its cap is unscrewed, thus indicating that from that manifold on down to the filters 50 the system is clear and normal. When a clogged pipe is thus located it is a simple matter to remove the caps of the manifold to which the clogged pipe is connected and insert a fish wire or cable into the pipe 55 through the opening in the manifold.

In order to facilitate the cleaning of the system I prefer that wherever possible the various pipes be arranged as straight and direct as possible, but if it is necessary to 60 provide bends in the pipe I prefer that these bends be made on a long radius so as to avoid sharp turns. I also prefer to provide suitable joints or couplings H in the various pipes so as to facilitate the removal 65 of the pipes if desired.

The outgoing pipes from the manifolds (such as the mains E, see Fig. 3) are preferably connected to the manifolds slightly above the bottom wall thereof so as to leave a pit J into which the larger impurities 70 such as bugs, lint and the like, may collect. This sludge may be readily removed through the cap-covered openings.

In installing a system of this character the best results are best accomplished by 75 studying the particular conditions and then grouping or arranging the manifolds and pipes accordingly. It will be noted the system is flexible and may be arranged to adapt it to various conditions, all without 80 departing from the spirit of my invention, and accordingly I do not desire to be limited to the particular arrangement shown.

What I claim as new and desire to secure by Letters Patent, is:

85

1. An oil drip return system comprising a return main, a junction box connected in series in the return main, drain pipes, group manifolds to which some of the drain pipes are connected, and means connecting each 90 group manifold with a junction box.

2. An oil drip return system comprising a return main, junction boxes in series in the return main, lateral pipes leading from the junction boxes, group manifolds connected to the lateral pipes, and drain pipes, some of which lead to the group manifold, and others to the main junction boxes.

95

3. An oil drip return system comprising a plurality of independent groups, oil 100 drains, each of which communicates with a separate source of oil drippings, a common manifold for each of said groups, a return main, junction boxes in series with the return main, an individual pipe leading from 105 each manifold at a point below the entrance thereto of said drains to one of the junction boxes and normally adapted to maintain said manifold substantially drained of its contents, and a closure for each manifold 110 and junction box whereby access may be had to the interior thereof.

110

4. An oil drip return system comprising a return main, a junction box connected in series with the main, a plurality of individual oil drains communicating with and adapted to receive oil drippings from a plurality of separate sources, and a manifold for the individual oil drains connected with a junction box, the drains and the return 120 main having sufficient pitch to cause the oil to flow therethrough by gravity.

115

5. An oil drip return system comprising a plurality of groups of oil drains, a manifold junction box for each group, another junction box connected with the manifold junction box of each group, a common return main in series with one or more junction boxes adapted to drain the oil from the junction boxes as fast as it is delivered 125 130

thereto from the manifold junction boxes, and removable covers for the junction boxes above the points where the oil enters.

6. An oil drip return system comprising
 5 a plurality of common junction boxes, a return main connected in series with the junction boxes adjacent the bottom thereof, a plurality of groups of oil drains, a manifold junction box for each group of drains,
 10 and a pipe connecting each manifold junction box at a point below the entrance points of the drains and connected to a common junction box at a point above that at which the return main is connected.
 15 7. An oil drip return system comprising a plurality of common junction boxes, a common return main connected in series with the boxes, a plurality of oil drain pipes, some of which are arranged in groups, and
 20 some connected directly to the common junction boxes at points above the connection with the return main, a manifold junction box for each group of drain pipes, and a pipe forming connection from the manifold junction box at a point below the entry of the drains and the common junction box at a point above the connection with the return main, all of the pipes being inclined to discharge to the common junction boxes.
 25 8. An oil drip return system comprising junction boxes, group manifolds each connected to a junction box, a plurality of drip collecting receptacles arranged about and at a distance from the boxes and manifolds,
 30 and a drain pipe for each receptacle, some of which extend to the boxes and some to the manifolds each having an unbroken bore at any place where the direction of flow is changed.
 35 9. An oil drip return system comprising an inclosed return main, junction boxes in

the return main, group manifolds each connected with one of the boxes, drip collecting receptacles, a drain pipe extending from each receptacle to a manifold or box, the receptacles being above the manifolds and the manifolds being above the boxes to drain thereto, the boxes and manifolds being each provided with an access opening above the drain and discharge connections, and adjustable caps for the openings which may be slightly opened to show, by leakage from its opening, where the system is obstructed.

10. In an oil drip return system, the combination with drip collecting receptacles, group manifolds for a number of receptacles and main junction boxes, of pipes connecting them so that they will drain by gravity to the lowermost, each box and manifold being provided with an opening above the connecting pipes thereto, and a tight-fitting but adjustable cap for each opening which can be slightly opened to show, by leakage from its opening, the place where the return pipe is obstructed.

11. In an oil drip return system, the combination with drip collecting receptacles, group manifolds and common junction boxes, of pipes connecting them for draining liquid to the lowermost point of the system, each pipe in which the direction of flow is changed being formed with an unbroken bend so that there will be the least tendency for the pipes to clog at the bend.

In testimony whereof I have signed my name to this specification, in the presence of two subscribing witnesses, on this 29th day of December A. D. 1911.

WILLIAM L. MORRIS.
